UNITED STATES PATENT OFFICE

157,726

DESK

James R. Batten, Oakland, Calif.

Application September 23, 1947, Serial No. 141,543

Term of patent 3½ years

(Cl. D33—7)

To all whom it may concern:

Be it known that I, James R. Batten, a citizen of the United States, residing at 2320—55th Avenue, in the city of Oakland, county of Alameda, and State of California, have invented a new, original, and ornamental Design for a Desk, of which the following is a specification, reference being had to the accompanying drawing, forming part thereof.

In the drawing

Fig. 1 is a perspective view of the desk, and
Fig. 2 is a front elevation of the same.

I claim:

The ornamental design for a desk, as shown.

JAMES R. BATTEN.
